UNITED STATES PATENT OFFICE.

LORNE HUGH MACORQUODALE, OF LYNN, MASSACHUSETTS, ASSIGNOR TO FORBES LITHOGRAPH MANUFACTURING COMPANY, OF BOSTON, MASSACHUSETTS, A CORPORATION OF MASSACHUSETTS.

CONSTRUCTION OF DISPLAY SCREENS AND THE LIKE.

Application filed October 30, 1918. Serial No. 260,239.

To all whom it may concern:

Be it known that I, LORNE H. MACORQUODALE, a citizen of the United States, and resident of Lynn, county of Essex, State of 5 Massachusetts, have invented an Improvement in the Construction of Display Screens and the like, of which the following description, in connection with the accompanying drawings, is a specification, like characters 10 on the drawings representing like parts.

This invention relates to structures which are built up from sheets, such as cardboard sheets, which usually are relatively stiff although somewhat yielding. My invention 15 contemplates a structure of this character embodying an improved form of joint between sheets which may, if desired, serve as a hinge. As an example of the type of structure referred to, I may mention the so-called 20 display screens designed to display advertising matter and consisting of a number of sheets hinged together and adapted to be placed in angular relation so that the whole will stand on end. Such structures are usually in the form of a triptych. As I believe 25 that a major field of application of the principles of my invention will be found in the construction of display screens, I have chosen such an article as an example for 30 purposes of description herein, and have illustrated one in the accompanying drawings wherein:—

Figure 1 is a front view of a triptych display stand embodying my invention;

Fig. 2 is a back view of the adjoining edges of one of the back sheets and one of the side sheets;

Fig. 3 is an enlarged detail with the parts separated; and

Fig. 4 is an end view of the display screen folded for carriage.

Referring to Fig. 1 of the drawings, I have there shown a display screen comprising a back sheet 5 to the sides of which are hinged 45 side pieces 7, the whole adapted to stand up in the manner indicated in the figure. It will be understood that suitable advertising matter, usually an attractive picture, will ordinarily be placed upon the faces of the 50 sheets.

It has hitherto been customary to connect the elements of the display screen by a hinged joint provided by an adhesive tape applied to the meeting edges of the sheets,

and the joint thus provided has sometimes 55 been reinforced by driven fastenings. For the larger and heavier screens such joints have not proved sufficiently strong or durable and their construction has entailed considerable handling and expense. In accordance with my invention I provide a conveniently formed type of joint which permits the sheets to be readily assembled but cannot readily be disconnected. For this purpose, assuming that a triptych is in question as herein disclosed, I may cut along the opposite edges of the back sheet 5 slots 9 and 11 and form on an edge of the sheets 7 cooperating tabs 13 and 15 adapted to enter the slots and be locked therein, providing a 60 joint which will permit hinging action because of the springy yielding of the millboard or other material of which the screen is made. The screen may thus be folded into the form shown in Fig. 4 and one piled upon 65 the other for shipment or storage. The slots (see Fig. 3) may be stamped from the sheet 5 when it is cut as may likewise the projecting tabs, this facilitating the manufacture of the screen. I believe that I am the first to 70 devise a display screen or like foldable and unfoldable structure comprising a plurality of serially connected sheets wherein the sheets are hingedly connected by means of 75 a slot and tongue construction.

In the form of the invention herein disclosed the joint between the sheets 5 and 7 is formed by two headed tabs 13 adjacent the top and bottom sides of the sheet 7, and an intermediate plain tab 15. The headed tabs 90 13 are adapted to be locked in slots 9, preferably of the particular construction herein-after described, by inserting them therein and then effecting a longitudinal movement 95 of the sheet along the line of junction of the two sheets so that an end of the slot will engage the neck 17 which defines the head 19 of the tab 13 and lock behind the shoulder of the latter. Conveniently the tab 15 is a plain unheaded tab and the slot 11 is 100 adapted to fit the same and is positioned to receive it when the headed tabs are locked in their slots after the longitudinal movement. The screen may thus be assembled by inserting the tabs 13 and springing the sheet 5 to 105 cause the middle portion thereof to belly outwardly, thus accommodating the tab 15 in the concavity thus formed. The headed

tabs 13 are then locked in their slots 9 by a longitudinal movement which will bring the tab 15 in line with its slot 11. The sheet 5 is then allowed to spring back so that the 5 tab 15 will enter the slot 11 and thus the whole structure is locked against longitudinal movement. The sheets cannot be disengaged until the sheet 5 is first sprung to release the tab 11, after which the tabs 13 10 may be manipulated to unlock them from their slots.

Herein (see Fig. 3) I have shown the slot 9 as embodying a straight portion 21 in line with the slot 11 and of a length substantially equal to the neck 17 of the tab 13 to fit the same and lock the head 19 of the tab. Opening from the straight portion 21 adjacent one end thereof is an extension 23 oblique to the portion 21. The 20 extension may either be straight, as shown, or slightly curved, and preferably where it joins the slot 21 one end of the slot, herein the upper end, defines a shoulder 25 adapted to make contact with one side of the neck 25 17 of the tab when it is housed in the portion 21 of the slot.

The portions 21 and 23 taken together constitute an auxiliary bent slot, the length of which corresponds to the dimensions of 30 the head 19 of the tab so as to permit the latter to be passed therethrough. In other words, it should be at least as long as the distance from one side of the neck to the opposite side of the head, in which case the 35 tab could be passed therethrough by a button-holding action if it had opposed shoulders as herein illustrated; but it is preferably of a length corresponding to the greatest dimension of the tab.

40 To insert the tab 13 in the slot 9, the sheet 7 is somewhat sprung so that the tab itself will assume a more or less bent form corresponding to the form of the slot 9 embodying the portions 21 and 23. It may 45 then be inserted through the slot and slid downwardly until the lower side of the neck 17 engages the bottom of the portion 21. As this portion 21 corresponds in length to the width of the neck 17, the upper portion 50 of the neck will then have moved free of the deflected extension 23 of the slot and the sheet 7 will snap over, lodging the upper part of the neck beneath the shoulder 25 and, in the present instance, the upwardly extending shoulder of the head 19 behind the sheet above that shoulder.

To release the joint thus formed, the sheet 7 must be sprung to release the neck from the shoulder 25 defined by the notch projecting from the convex side of the bent slot formed by the portions 21 and 23 and then slid longitudinally to release the lower shoulder of the head and permit the tab to be withdrawn.

65 Preferably, as already described, a joint

is formed by at least two tongue and slot joints such as have just been described and which are illustrated in Fig. 3 in cooperation with a slot 11 and plain corresponding tongue 15. In such a construction, as shown 70 in Fig. 2, the oblique extensions 23 preferably extend in the same direction while the portions 21 of the slots are preferably straight and align with each other and with the slot 11.

A construction of this kind has been found easy to assemble but when made of fairly heavy materials it practically requires the effort of two persons to disassemble it. The joint is strong in all directions since the tabs 13 are preferably provided with heads 19 having shoulders on each side and locking at each end of the straight portions 21 of their slots, and the folding of the screen to the form shown in 85 Fig. 4 does not cause any substantial disrupting strain.

Having thus described the illustrative embodiment of my invention as shown in the accompanying drawings, the principles exemplified thereby which I consider new and desire to secure by Letters Patent I shall define in the following claims:—

1. A display screen or like article comprising a pair of relatively flexible sheets, 95 one sheet having a headed tab and a plain tab and the other having a slot to receive the headed tab and a slot to receive the plain tab when a shoulder of the head of the headed tab is locked by an end of the 100 slot.

2. A display screen or like article comprising a pair of relatively flexible sheets, one sheet having a pair of headed tabs at one end adjacent the sides thereof and a plain tab between them and the other having slots to receive said headed tabs and lock behind the heads thereof and a slot positioned to receive the plain tab when the headed tabs have been locked. 105

3. A display screen or the like comprising a pair of relatively flexible sheets, connecting means adjacent opposed sides thereof adapted to interlock by longitudinal movement in the direction of the line of junction and cooperating male and female parts on the sheets arranged for engagement after such movement and adapted to be separated by springing of one of the sheets. 115

4. A triptych display screen comprising 120 three relatively stiff sheets adapted to be folded together or to stand on edge and mutually support one another when the sheets are unfolded and in this position to display matter on their faces, one sheet having vertically aligned slots along its sides and others having tabs projecting from edges thereof fitting in and locked against withdrawal from said slots. 125

5. In a joint construction one element 130

having a headed tab and a plain tab, a second element having a slot of a size to receive the neck and lock behind the head of said headed tab and an offset extension 5 opening from said slot providing in cooperation therewith an auxiliary slot of a size to pass the head, said element also having a slot positioned to receive said other tab when the headed tab is locked in its 10 slot, and thereby to hold the head engaged.

6. In a joint construction one element having a pair of headed tabs and an intermediate plain tab, a second element having

slots positioned to receive the headed tabs of a size to receive the necks and lock behind the heads thereof and extensions opening in the same direction from said slots providing in cooperation therewith auxiliary slots of a size to pass the heads, said element also having a slot to receive said other tab when the headed tabs are locked in their slots, and thereby to hold the heads engaged. 15

In testimony whereof, I have signed my name to this specification.

LORNE HUGH MACORQUODALE.
